[57] CLAIM

The ornamental design for a building, substantially as shown and described.

DESCRIPTION

FIG. 1 is a front elevation of a building showing our new design;

FIG. 2 is a front elevation view thereof taken from a different azimuthal position than in FIG. 1;

FIG. 3 is a perspective view thereof taken from the same azimuthal position as FIG. 1; and

FIG. 4 is a top view thereof.

FIG. 3FIG. 4
